UNITED STATES PATENT OFFICE.

ROBERT R. GOLDTHORP, OF HARTFORD, CONNECTICUT.

TUNING-TRANSFORMER FOR WIRELESS SYSTEMS.

1,134,840.

Specification of Letters Patent.

Patented Apr. 6, 1915.

Application filed December 15, 1913. Serial No. 806,776.

To all whom it may concern:

Be it known that I, ROBERT R. GOLDTHORP, a citizen of the United States, and a resident of Hartford, in the county of Hartford and State of Connecticut, have invented a new and Improved Tuning-Transformer for Wireless Systems, of which the following is a full, clear, and exact description.

10 This invention relates to a tuning transformer for wireless systems and relates more particularly to a transformer of that type having relatively movable primary and secondary coils in connection with means for 15 varying the effective lengths of the coils to obtain a wide range of tuning capacity.

The invention has for its general objects to improve and simplify the construction and operation of transformers of the character referred to so as to be reliable and efficient in use, composed of comparatively few parts, inexpensive to manufacture and keep in operative condition, and capable of quick, easy and accurate adjustment.

25 Another object of the invention is the provision of a transformer having a novel arrangement of inductively related coils of simple and novel design, whereby extremely fine and sharp tuning is rendered possible, 30 such coils being wound flat and elongated, and pivoted co-axially together in the closest proximity possible, whereby tuning can be effected by shifting the movable coil through an arc of ninety degrees, from one 35 extreme to the other, which adjustment, together with the changing of the effective lengths of the respective coils, gives an extremely wide range of tuning.

Another object of the invention is that 40 extreme close coupling between primary and secondary is obtained; therefore less loss of energy in the secondary.

Still another object is to so mount the movable coil that in addition to its angular 45 adjustment with respect to the other coil, it can be moved bodily to and from the relatively fixed coil for the purpose of increasing the tuning range.

With such objects in view, and others 50 which will appear as the description proceeds, the invention comprises various novel features of construction and arrangement of parts such as will be set forth with particularity in the following description and 55 claims appended hereto.

In the accompanying drawings, which

illustrate certain embodiments of the invention, and wherein similar characters of reference indicate corresponding parts in all the views, Figure 1 is a view of the transformer as seen from underneath, as when the bottom plate of the casing is removed; Fig. 2 is a sectional view on the line 2—2, Fig. 1; Fig. 3 is a plan view of one of the windings or coils of the transformer; Fig. 4 is a plan view of the adjusting knobs for the movable coil and the switches; Fig. 5 is a diagrammatic view of the transformer windings; and Fig. 6 is a perspective view of a modified form of transformer, wherein the movable coil has both rotative and axial movement.

Referring to the drawing, A designates the casing that incloses the transformer and which consists of a back or bottom plate 1 and a chambered body or cover 2, such casing being made of some suitable insulating material. Rotatably mounted within the casing is an approximately elliptical plate or support B of insulating material which 80 has one surface disposed adjacent to the inner surface of the cover 2 of the casing, and the juxtaposed faces have the coils or windings of the transformer, the primary coil p being fastened to the plate or carrier 85 B and the secondary coil being fastened to the cover 2.

The primary element is rotatably supported by means of a tubular shaft or axle 3 which has a shouldered end fitted in an 90 opening 4 in the plate B, and a shouldered bushing 5 is fitted in the tubular axle 3 to cooperate with the shoulder of the latter for securing the plate B to the axle. This axle has on its outer end a knob 6 or equivalent 95 device for enabling the axle to be turned in order to change the angular relation of the primary to the secondary coil for varying the inductive effect. The axle is journaled within a sleeve or tubular bearing 7 which 100 extends out of the casing through an opening 8 in the center of the cover 2.

The windings or coils are mechanically the same, except that of course the primary winding is made of wire of coarser 105 gage than the secondary winding. Each winding or coil is absolutely flat and is approximately elliptical or elongated. A cardboard or other plate 10 forms a base on which the wire is secured. This plate 110 10 is mounted in a suitable coil-forming device, and the surface of the plate is shel-

lacked. The wire is then wound into a coil and adheres to the plate by means of the shellac or equivalent material, and after the coil is completely formed the whole 5 winding may be again shellaced. Loops or taps 11 are provided at various points in the coil so as to divide the latter into a plurality of sections whereby more or less of the coil can be connected in circuit by a 10 multi-point switch. The coils when completed are secured in place by the back surfaces of the plates 10 being glued or otherwise fastened to the carrier B and cover 2. The primary winding *p* has its loops or 15 taps connected with contact points 12 which are arranged on the side of the carrier B opposite from that which has the winding, and a movable contact or spring 13 is adapted to engage the contact points 12 so as to 20 connect more or less of the primary winding in circuit. The movable contact 13 is fastened to a spindle or rod 14 which passes through the axle and has one end journaled in the bushing 5 and the other end journaled 25 in the bushing 15 in the outer end of the axle, there being a knob 16 fastened to the outer end of the spindle so as to turn the same, the spindle 14 being rotatable with the axle when the knob 6 is turned for 30 the purpose of changing the position of the primary winding. In order to connect the primary winding, which is movable, with the outside circuit, a split ring or annular contact 17 is fastened to the carrier B in 35 concentric relation to the axis of rotation, and the terminal 18^a of the primary winding is connected with this ring, while the various sections of the winding are connected with the respective contact points 12. 40 Bearing on the ring is a spring contact 18 which is fastened to the back plate 1 and is connected by a wire 19 with the primary binding post 20 on the cover of the casing. The other primary binding post 21 is connected by a wire 22 with a contact 23 fastened to the back 1 in such a position that its free end constantly bears on the spindle 14, which serves to electrically connect the 45 switch contact 13 with the contact 23. 50 The secondary winding has its loops or taps connected with contact points 24 which are arranged on the outside of the cover 2 in an arc around the center thereof, and arranged to engage these contact points is 55 a spring contact 25 which is fastened to a knob 26 rotatable on the tubular bearing 7. A metallic spring washer 27 is in electrical engagement with the hub of the contact 25 and also in engagement with a metal plate 60 or washer 29, which bears on the cover 2 and is electrically connected by a wire 30 with the secondary binding post 31. The other binding post 32 is connected by a wire 33 with one terminal of the secondary winding *s*, while the other terminal in this wind-

ing is connected with the last contact point 24 of the secondary switch. The knobs 26 are spaced apart by a collar 34 which is fastened to the tubular bearing 7. On the cover is an indicating device or mark 35 70 with which co-operates a finger 36 on the knob 6, the finger being so arranged that when the same is opposite the indicating device 35, the primary and secondary windings will be positioned with their major axes 75 parallel, which produces maximum inductance. The knob 6 can be turned to the right or left in order to throw the major axes of the coils out of parallelism, whereby the straight portions of one coil will intersect the straight portions of the other coil and change the inductive effect, it being understood that the minimum inductance is obtained when the major axes of the coils are at right-angles to each other. For facilitating the adjustment of the primary coil as regards its effective length, the outer surface of the knob 6 is provided with a scale 37 over which projects an index finger 38 on the knob 16, and by the position of this 80 finger with respect to the divisions of the scale it is possible to ascertain how many sections of the primary coil are in circuit. 85

In the modification shown in Fig. 6 the primary and secondary elements are design- 95 nated P and S, the coils thereof being the same as in the construction previously described. The secondary element S is rotatably mounted on an axle or post 40 so as to obtain an angular adjustment of the coils, 100 but this post also enables the secondary element S to be adjusted axially away from or toward the primary element, it being understood that the transformer is so mounted on a support that the post 40 will be horizontal, so that the secondary element will remain in any position of adjustment toward or from the primary element. 105

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made when desired as are within the 115 scope of the appended claims. 120

Having thus described my invention, I claim as new and desire to secure by Letters Patent:

1. A tuning transformer comprising flat, 125 elongated primary and secondary windings arranged co-axially and relatively adjustable from a position with the major axes parallel to a position with the said axes at right-angles to each other. 130

2. A tuning transformer comprising flat, elongated primary and secondary windings arranged co-axially and relatively adjustable from a position with the major axes 5 parallel to a position with the said axes at right-angles to each other, and means for permitting movement of the coils toward and from each other.
3. A tuning transformer comprising two flat, elongated parallel primary and secondary coils pivotally connected for rotation through an arc of ninety degrees, and means for varying the effective length of each coil.
- 15 4. A tuning transformer comprising two flat, elongated parallel primary and secondary coils pivotally connected for rotation through an arc of ninety degrees, and a multiple-point contact switch for changing 20 the effective length of each coil.
5. A tuning transformer comprising a stationary coil, a movable coil, a tubular axle connected with the movable coil, said coils being flat and parallel and elongated, 25 means for turning the axle to change the position of the coils, contact points connected with the movable coil for dividing the same into sections, a movable contact for engaging the contact points, a spindle journaled in the axle and connected with the movable contact for moving the same, means 30 for connecting through the said contact and contact points the movable winding with a circuit, and a slip ring contact connection for connecting the movable winding in circuit, contact points connected with the fixed winding, and a movable contact rotatable about the axes for engaging the last-mentioned contacts.
6. A tuning transformer comprising a stationary coil, a movable coil, a tubular axle connected with the movable coil, said coils being flat and parallel and elongated, 35 means for turning the axle to change the position of the coils, contact points connected with the movable coil for dividing the same into sections, a movable contact for engaging the contact points, a spindle journaled in the axle and connected with the movable contact for moving the same, means 40 for connecting through the said contact and contact points the movable winding with a circuit, a slip ring contact connection for connecting the movable winding in circuit, contact points connected with the fixed winding, and a movable contact rotatable about the axes for engaging the last-mentioned contacts.

In testimony whereof I have signed my 55 name to this specification in the presence of two subscribing witnesses.

ROBERT R. GOLDTHORP.
